UNITED STATES PATENT OFFICE.

CHARLES BALOUGH, OF SPRINGFIELD, OHIO, ASSIGNOR TO THE HERCULES MOTOR MANUFACTURING COMPANY, OF CANTON, OHIO, A CORPORATION OF OHIO.

PRESSURE-GOVERNOR.

1,268,421.

Specification of Letters Patent.

Patented June 4, 1918.

Application filed April 20, 1916. Serial No. 92,501.

To all whom it may concern:

Be it known that I, CHARLES BALOUGH, a subject of the Emperor of Austria-Hungary, residing at Springfield, in the county 5 of Clark and State of Ohio, have invented certain new and useful Improvements in Pressure-Governors, of which the following is a specification.

This invention relates to improvements in 10 governors, the governor shown being one particularly designed for regulating the speed of internal combustion engines and being arranged to be operated by fluid put under pressure by the engine.

15 The object of the invention is to provide a governor which will be simple in construction and effective in operation and also one in which friction of the moving parts will be reduced to the minimum.

20 In the accompanying drawings:—

Figure 1 is a side elevation of a portion of an internal combustion engine, showing my improved governor applied thereto, the governor and some of the parts of the engine being shown in section.

25 Fig. 2 is a section on the line 2—2 of Fig. 1.

Fig. 3 is an enlarged view of a portion of the devices shown in Fig. 1.

30 In the present instance, I have illustrated the governing mechanism connected with the oiling system of the engine, this system being such as is now commonly in use in connection with automobiles. In carrying out 35 the invention, I employ a piston or plunger, 1, located in a suitable chamber or cylinder which is in direct communication with the oil. It is immaterial at what particular point this plunger is applied, but in the 40 present case I have shown the plunger located in the hollow hub 2 of a gear 3 which forms a part of the operating mechanism connected with the engine. The bearing 4 for the gear hub is in communication with 45 an oil pump 5 through the passageway 6 and oil under pressure will find its way to the interior of the hub 2 through the groove 7 and opening 8 leading from the groove to the interior of the hub. The piston 1 has 50 connected therewith a rod 9 which is slidably mounted in guides 10, the rod being provided with a flattened portion 11 and one of the guides provided with a correspondingly shaped orifice to prevent the rod from

turning. Connected to the end of the rod is 55 a head 12 provided with an inclined surface 12^a. In the present case I have shown the valve mechanism as being located in the intake manifold 13. 14 is a stationary sleeve located in the chambered portion of the support 15 for the manifold and extending through the manifold into a chambered portion 16. Slidably arranged in the stationary sleeve 14, is a movable sleeve 17 closed at the top and bottom but provided with 60 ports 18 arranged to coöperate with ports 19 in the stationary sleeve 14; these ports being arranged in the manifold 13. The lower end of the closed sleeve 17 has a stem 20 which extends down through the support 15 65 and has its lower end provided with an anti-friction roller 21 which is maintained in contact with the inclined surface 12 of the piston rod by a spring 22 interposed between the upper end of the sleeve 17 and the closure 23 for the chamber 16. The cap 24 which closes the upper end of the movable sleeve 17 projects laterally beyond the same so as to coöperate with the stationary sleeve 14 to provide a stop. 70

When the piston 1 is at its extreme inner position in the hollow hub, the ports 18 and 75 19 will be in complete registry with each other so as to allow the maximum amount of fuel to pass through the intake manifold. 80 As the speed of the engine and consequently the pressure of the oil, increases the piston 85 will be forced outwardly causing the inclined surface of the piston rod to force the stem 20 and sleeve 17 upwardly against the tension of the spring so as to partly or completely close the ports. As the speed of the engine, and consequently the flow of the oil, decreases the spring 22 will force the parts 90 in the opposite direction to increase the supply of fuel. The closure 23 is in the nature of a screw-threaded plug which provides 95 means for adjusting the tension of the spring.

Having thus described my invention, I 100 claim:—

1. In a governing mechanism for a motor, a source of motive energy for said motor together with driven devices, a source of lubricating fluid pressure controlled by the motor, a piston located near the center of one of the driven devices arranged to be acted upon by said fluid, a valve for the motive

- 2
- energy comprising a slidable ported sleeve, and a connection between said piston and said sleeve.
2. In a governing mechanism for a motor, 5 a source of motive energy for said motor, a source of fluid under pressure controlled by said motor, a piston in communication with said fluid, a spring pressed ported sleeve for controlling said motive energy, an inclined 10 block connected with said piston, and a valve stem connected with said sleeve coöperating with said block.
3. In a governing mechanism for a motor, 15 a source of motive energy for said motor, a source of fluid under pressure controlled by said motor, a piston in communication with said fluid, an inclined block connected with said piston, a spring pressed valve comprising two ported sleeves one of which is movable with respect to the other, and a stem 20 connected with said movable sleeve and coöperating with said inclined block.
4. In a governor for internal combustion engines, a source of fuel together with an 25 intake manifold for the same, a source of fluid under pressure controlled by said motor, a piston in communication with said
- fluid, a piston rod connected with said piston having an inclined surface, a fuel valve arranged in said manifold consisting of two 30 ported sleeves, one of which is movable with respect to the other, a valve stem connected to one of said sleeves coöperating with said inclined surface to move said sleeve in one direction, and a spring for 35 moving said sleeve in the opposite direction.
5. In a governing mechanism for a motor, a source of motive fluid for said motor together with gear mechanism driven by said motor, a source of lubricating fluid under 40 pressure controlled by said motor, a cylinder and piston arranged near one of said driven devices whereby the piston cylinder will be in line with the bearing for the driven device, said piston being arranged to be acted upon by said lubricating fluid, and devices for controlling said motive fluid, substantially as specified.

In testimony whereof, I have hereunto set my hand this 13th day of April, 1916.

CHARLES BALOUGH.
